(57) **CLAIM**

I claim the ornamental design for a dog bone chew consumable, as shown and described.

DESCRIPTION

FIG. 1 is a perspective view of a dog bone chew consumable showing my new design;

FIG. 2 is a left side elevation view of the dog bone chew consumable shown in FIG. 1, the right side elevation view being a mirror image thereof;

FIG. 3 is a top view of the dog bone chew consumable shown in FIG. 2, this view being identical to the view in the direction of arrows 3A and 3B shown in FIG. 2; and,

FIG. 4 is a bottom view of the dog bone chew toy shown in FIG. 2, this view being identical to the view in the direction of the arrows 4A and 4B shown in FIG. 2.

The broken line showing of a channel for receiving a treat illustrates a portion of the dog bone chew consumable which forms no part of the claimed design.
